UNITED STATES PATENT OFFICE

135,695

DESIGN FOR A COIN TRAY

George L. Allen, Lake Geneva, Wis.

Application July 24, 1942, Serial No. 107,664

Term of patent 3½ years

To all whom it may concern:

Be it known that I, George L. Allen, a citizen of the United States and a resident of Lake Geneva, in the county of Walworth and State of Wisconsin, have invented a new, original, and ornamental Design for a Coin Tray, of which the following is a specification, reference being had to the accompanying drawing, forming a part thereof.

The side opposite to that illustrated in Figure 1 is substantially the same as that shown.

I claim:

The ornamental design for a coin tray, as shown and described.

GEORGE L. ALLEN.
